United States Patent Office

Des. 210,660
Patented Apr. 2, 1968

210,660

AIRCRAFT SEAT

Frank J. Del Giudice, Seattle, Wash., assignor to Hardman Tool and Engineering Company, Los Angeles, Calif., a corporation of California

Filed Feb. 13, 1967, Ser. No. 5,793

Term of patent 14 years

(Cl. D15—8)

FIG. 1

FIG 2.

FIGURE 1 is a front perspective view of an aircraft seat showing my design where one of the headrest members is in an alternate position; and

FIGURE 2 is a rear perspective view thereof.
The end of the seat not shown is a mirror image of the end shown.

I claim:

The ornamental design for an aircraft seat, as shown and described.
